UNITED STATES PATENT OFFICE.

JOHN ROBERT WESTON, OF DUBUQUE, IOWA

ENGINE AND RADIATOR HEATER.

1,389,109.

Specification of Letters Patent. Patented Aug. 30, 1921.

Application filed December 16, 1920. Serial No. 431,223.

To all whom it may concern:

Be it known that I, JOHN R. WESTON, a citizen of the United States, residing at Dubuque, in the county of Dubuque and State 5 of Iowa, have invented certain new and useful Improvements in Engine and Radiator Heaters; and I do declare the following to be a full, clear, and exact description of the invention, such as will enable others skilled 10 in the art to which it appertains to make and use the same.

This invention relates to an improved heater for use in connection with the engine and radiator of an automobile or other 15 motor driven vehicle, and one object of the invention is to provide a heater in which the burner or other source of heat may be mounted in a housing, the burner having a discharge or draft pipe extending through 20 the roof of the housing and an auxiliary roof or hood being placed above the housing to provide an air space through which air may pass and into a pipe inclosing the extended end portion of the discharge pipe 25 to permit the products of combustion to form a suction which will draw the air into the air pipe.

Another object of the invention is to so construct this heater that the air which is 30 drawn into the pipe from between the auxiliary roof or hood and the roof of the housing may be thoroughly heated and the warm air additionally heated by being mixed with products of combustion passing out through 35 the extended end of the discharge pipe.

Another object of the invention is to so construct this heater that the burner may be provided with a fuel reservoir having a supply pipe leading through the housing 40 and terminating in a measuring receptacle in the form of a funnel thereby permitting a desired quantity of fuel to be delivered to the fuel reservoir when a valve controlling passage of the fuel through the supply pipe 45 is opened.

Another object of the invention is to so construct this heater that a storage tank may be provided with an outlet pipe terminating above the funnel or measuring receptacle thus permitting the liquid fuel to be delivered to the receptacle and a measured quantity thereof then delivered to the reservoir of the burner;

This invention is illustrated in the accompanying drawings, wherein:

Figure 1 is a view partially in section and partially in elevation and showing the device in use.

Fig. 2 is a perspective view of the hood which fits over the motor.

This heater is provided with a housing 1 having a doorway 2 for permitting access to the interior of the housing, a door or other suitable closure 3 being provided so that the doorway may be closed when the 65 heater is in operation. Openings 1' are provided in the walls of the housing so that air may pass into the housing to supply the necessary air for the liquid fuel burner 4 positioned in the housing and resting upon the flooring thereof. This burner 4 is of a conventional construction and is provided with the usual reservoir 5 for holding the fuel. A supply pipe 6 extends from the reservoir 5 through one of the side walls of 70 the housing and has its outer end portion extending upwardly and connected with a measuring cup 7 which constitutes a funnel for the pipe 6. A valve 8 is provided so that a desired quantity of the liquid fuel 75 may be fed into the measuring cup and the valve then opened and the fuel permitted to pass through the pipe 6 into the reservoir 5 of the burner. A storage tank 9 is supported upon a suitable shelf or other support 10 and is provided with a valve controlled outlet 11 which terminates above 80 the measuring cup 7 thus permitting the fuel to be fed into the measuring cup by simply opening the valve of the pipe 11, the valve 8 being closed.

The burner 4 is provided with a discharge pipe 12 which forms a chimney for the burner. This discharge pipe extends up through the roof of the housing and extends 95 into a heated air pipe 13 which is provided at its lower end with a flaring hood 14 which forms an auxiliary roof for the housing and is supported in spaced relation to the roof of the housing thus providing space through 100 which air may pass in order to enter the pipe 13 through its lower end. It will thus be seen that this air will be heated before it enters the pipe 13 to its passage through the space between the hood 14 and the roof of 105 the housing. It will be further noted that

the passage of the products of combustion through the pipe 13 from the discharge pipe or chimney 12 will cause a suction in the pipe 13 and tend to draw the air into the outer pipe through the lower end thereof. This pipe 13 is provided with an elbow 15 so that the hot air pipe may be extended to the point where the automobile or other motor vehicle is usually placed when not in use. A hood 16 has been provided at the outer or free end of the hot air pipe 13 and this hood which is provided with side walls and a roof as shown, is open at one end and at its second end is provided with a head 17 which tapers to and is connected with the pipe 13. It will thus be seen that the hood 16 may be placed to inclose the motor and radiator of an automobile and the heated air from the pipe 13 will pass into this hood and will serve to keep the motor and radiator warm and prevent freezing of the water in the radiator and further prevent the engine from becoming cold. When a motor has been standing idle all night and has become chilled, it is difficult to start the motor and it is to prevent the motor from becoming cold and to prevent freezing of the water in the radiator that this device has been provided. The pipe 8 may be of a rigid construction and the automobile driven into the proper position to place the motor and radiator within the hood 16 or the pipe 13 may be of a flexible construction and properly placed upon the motor and radiator after the automobile has been brought to a stop.

There has thus been provided a device of the character described which will operate very efficiently and will supply heated air to the motor in a sufficient quantity to prevent freezing of the water and prevent the motor from becoming chilled. There has further been provided a heater so constructed that when the device is in operation and the reservoir 5 needs refilling, it is not necessary to open the housing and remove the burner, but it is only necessary to fill the measuring cup and then open the valve 8 and permit the fuel to pass down through pipe 6 into the reservoir.

50. What is claimed is:

1. A heating device comprising a housing having a roof of heat conducting material,

an auxiliary roof for said housing supported above the roof of the housing to provide an air passage between the housing roof and auxiliary roof, a heater in the housing having a discharge pipe extending through the roof of the housing in air-tight engagement with the housing roof and through an enlarged opening in the auxiliary roof, and an air conducting pipe extending from the opening in the auxiliary roof with the discharge pipe of said stove extending partially through the air pipe, in spaced relation to the same. 65

2. A heating device comprising a housing having a roof of heat conducting material, an auxiliary roof spaced above the roof of the housing to provide an air passage between the housing and auxiliary roof, a heater in the housing having a discharge pipe extending through the roof of the housing and through an opening in the auxiliary roof and having air-tight engagement with the housing roof, an air conducting pipe extending from the opening in the auxiliary roof in spaced relation to the discharge pipe and inclosing the extended portion of said discharge pipe, and a hood for inclosing the article to be heated communicating with said air pipe. 75

3. A heating device for an automobile motor and radiator comprising a housing having a tapered roof of heat conducting material, an air collecting hood spaced above the roof of the housing and having an air outlet opening, a heater in the housing having a discharge pipe extending through the housing roof and the outlet opening of the auxiliary roof and having air-tight engagement with the housing roof, an air pipe extending from the air outlet opening, and positioned about the discharge pipe in spaced relation to the same and a hood carried by the pipe for inclosing a motor and radiator. 80 90

4. The structure of claim 3 having the motor and radiator inclosing hood provided with side walls and a roof, one end of the hood being open and the second provided with a tapering head communicating with 100 the air pipe.

In testimony whereof I have hereunto set my hand.

JOHN ROBERT WESTON.
